PENDANT PULL FOR A SLIDE FASTENER

Allan O. Swan, Meadville, Pa., assignor to Textron Inc., Providence, R.I.

Filed Jan. 29, 1973, Ser. No. 327,531

Term of patent 14 years

Int. Cl. D2—07

U.S. Cl. D2—415

FIG. 1FIG. 2*FIG. 4*FIG. 3*FIG. 5FIG. 1 is an elevation view of a pull for a slide fastener showing my new design;

FIG. 2 is a side view of FIG. 1;

FIG. 3 is a cross section taken along the line 3—3 of FIG. 1;

FIG. 4 is a top plan view of FIG. 1; and

FIG. 5 is a bottom plan view of FIG. 1.

I claim:

The ornamental design for a pendant pull for a slide fastener, substantially as shown and described.
